UNITED STATES PATENT OFFICE.

HENRY C. HUNTER, OF HAMILTON, CANADA, ASSIGNOR, BY MESNE ASSIGNMENTS, TO THE CANISTER MANUFACTURING COMPANY, OF PHILLIPSBURG, PENNSYLVANIA.

ROLL-PRESS FOR FORMING WEAKENED LINES IN CAN-HEADS.

SPECIFICATION forming part of Letters Patent No. 654,256, dated July 24, 1900.

Application filed July 23, 1898. Serial No. 686,735. (No model.)

To all whom it may concern.

Be it known that I, HENRY C. HUNTER, a citizen of the United States, residing at Hamilton, Ontario, Canada, have invented certain new and useful Improvements in Roll-Presses for Forming Weakened Lines in Can-Heads or the Like, of which the following is a specification.

My invention relates to the making of heads for cans and canisters, and though not limited to any particular kind of head is more particularly designed for that class of cans or canisters shown in Letters Patent of the United States No. 492,806, granted to me on the 7th day of March, 1893. In cans and canisters of this class it is desirable to remove the head without disturbing the rim of the head, which is attached to the edge of the can-body. It is also desirable in any kind of cans, canisters, and the like in which the contents are used for domestic purposes that the head should be readily removable without the use of special tools. To this end a partial removal of the metal or material of the head on the line of required rupture has been devised in a simple and economical manner. My invention herein set forth includes the machinery for and the method of forming such a weakened line of uniform thinness, but without actual rupture, this not taking place until the head is intentionally severed.

The easy removal of the head without the use of a special tool requires that it be extremely thin on the weakened line. If this be done by stamping or by a graving-tool, there is danger that the line may be in some parts left too thick and that in some parts the metal may be cut to such a degree as to cause a break. To remedy this and to rapidly form the weakened line with absolute uniformity and certainty is the special object of my method, which consists in gradually applying pressure upon the head on the line to be weakened by means of dies movable one with relation to the other in planes a fixed distance apart, the initial pressure being preferably applied at the corner of the can-head.

My invention also includes the mechanism as herein set forth.

My invention is illustrated in the accompanying drawings, in which—

Figure 1 shows a side elevation in which parts are in section. Fig. 2 represents an end view with parts also in section. Figs. 3, 4, and 5 show detached parts and represent details of construction.

In the drawings the bed of the machine is shown at B, supported on a suitable standard A. It has a dovetail path in which slides a carriage C, formed with an inclined platform 60 2, on which is a wedge 3, whose incline is reversed to that of the platform, so that the upper surface of the wedge is level. On this upper surface is a stud 4, which holds the die 5. The wedge is adjustable to raise or lower 65 and so adjust the die in height by means of a screw 6. The wedge when adjusted is held by clamping-screws 7 and 8. The die is seated squarely and firmly on the wedge. Above the face of the die and with its axis in a line parallel with the face of the die is a roller D, having a plain cylindrical bearing-surface of hardened steel. It is mounted in bearings in the sides 9 of a frame E, which is a part of the bed-casting. On the ends of the axles of 70 the roller are shrunk sleeves 10 and 11, and on the ends of the roller are cog extensions 12. These cogs engage with rack-bars 13 on the carriage C, so that as the roller is turned it causes the carriage to move under itself. The 75 roller bears also on ribs 14 on the carriage to relieve the bearings. On the end of the sleeve 11 is a gear which engages with a rack-bar 15, which is held in engagement with the teeth of the gear 1 by means of an idle wheel 16. 80 (Shown detached in Fig. 3 and in place in Fig. 1.) The back of the rack-bar is grooved to engage with a rib on the idle wheel. The lower end of the rack-bar is pivoted to a wrist-pin 17 on the gear-wheel F, driven by a pinion G 85 on the main driving-shaft through pulley H. As the rack-bar is reciprocated it turns the roller first in one direction and then in the opposite, causing it to reciprocate the carriage and carry the die back and forth under 90 the roller while the roller turns. The rack-bar has a curved rear face, as shown in Fig. 1, so that it is wider at the upper and lower 95

bearing ends to compensate for the different angles it is compelled to assume and always to fit the space between the gear and the idle wheel.

5 The die is shown more clearly in section in Fig. 4. It may be of any configuration in plan required by the shape of the can. The form shown has rounded corners and flattened sides. A rib 21 around the edge is provided with a blunted edge adapted to form the groove in the head, which constitutes the weakened line.

The die is fitted to receive the stamped head resting on the rib 21. The head is put 15 on the die when the latter is in position shown in Fig. 1. The elevation of the die edge is regulated by the wedge, so that a very narrow space is left between said edge and the lower surface of the roller. As the die carrying the 20 head passes under this roller the plate of the head is pressed evenly and with absolute accuracy upon the die edge, and the said edge is sunk therein a distance determined by the space between the edge and the roller. This 25 sinking of the edge of the die into the metal by pressure leaves a very thin but compressed film of the metal or other material of the head, and this film, though compact and still impervious, is capable of easy rupture.

30 I am careful to arrange the die, as shown in Fig. 5, so that the corner first goes under the roller, and the work is thus done progressively and from the narrowest to the widest part by pressure between surfaces 35 having fixed limits in relation to each other, one of these surfaces being a roller, and this same progressive action would be carried out in the case of a round can.

I do not wish to limit myself to the use of a 40 roller, as it is practical to make the interstitial space of a determined size and rigidly exact with other forms of pressure means.

I claim—

1. In combination, a die having an edge 45 adapted to form a groove, and a roller adapted to extend from side to side over the die edge to act with different portions thereof in succession, means for determining the interstitial space between the die edge and roller 50 and means for moving one part in relation to the other whereby the roller will act progressively across the die from one edge to the other, substantially as described.

2. In combination, a flat die adapted to receive and hold a can-cap and having a die edge, a roller to act with said die edge, means for determining the interstitial space between the die edge and roller, and means for moving one of said parts in relation to the other 60 whereby the roller will act progressively across the die edge and from side to side of the die, substantially as described.

3. In combination, the roller turning in

fixed bearings, the die having an edge, a movable carriage supporting the die, and means 65 for reciprocating the carriage under the roller whereby the die will be carried under the roller to make the same act on different parts of the die transversely across its top, the said roller and die having a fixed limit in respect 70 to the interstitial space between them, substantially as described.

4. In combination, the roller mounted in fixed bearings having cogs, a carriage, a rack-bar thereon engaging with the cogs, means 75 for rotating the roller and a die mounted on the carriage, said carriage reciprocating under the roll to make the same act transversely across the top of the die from margin to margin substantially as described. 80

5. In combination with the roller having cogs, a die-carriage having a rack-bar engaging with the roller-cogs, a cog-wheel on the roller-shaft, and a rack-lever held in engagement therewith, said lever being operated by a wrist-pin, substantially as described. 85

6. In combination, in a machine for forming a weakened line in a can-head, a die having an edge adapted to form a groove and a roller having a fixed limit of action toward 90 the die edge to maintain a uniform interstitial space, said roller acting progressively from margin to margin of the die edge and transversely across the top of the die, substantially as described. 95

7. In combination, a plain-faced roll, the lineally-moving carriage and the die of rectangular or like form set upon the carriage with one of its corners in advance to go under the roll first, the surface of the roll and the edge of the die having a fixed limit in relation to the space between them substantially as described. 100

8. In combination with the roll and die-carriage geared together, the rack-bar for 105 turning the roll engaging a gear connected therewith, the wheel and crank-pin for reciprocating the rack, and the guide for the rack, said rack passing between the same and the gear-wheel and having a curved face, substantially as described. 110

9. In combination, the die having a cutting edge in one flat plane, and a roll having a fixed limit toward the die to maintain a uniform interstitial space, the plane of the die 115 being tangential to the periphery of the roller and the movement of the parts being progressive from margin to margin of the can-head and transversely across the top of the die, substantially as described. 120

In testimony whereof I affix my signature in presence of two witnesses.

HENRY C. HUNTER.
